UNITED STATES PATENT OFFICE.

JEROME B. SWEETLAND, OF PONTIAC, MICHIGAN.

WEIGHT-POWER.

SPECIFICATION forming part of Letters Patent No. 370,026, dated September 13, 1887.

Application filed March 23, 1887. Serial No. 232,124. (No model.)

To all whom it may concern:

Be it known that I, JEROME B. SWEETLAND, of Pontiac, in the county of Oakland, and in the State of Michigan, have invented a certain 5 new and useful Improvement in Weight-Power; and I do hereby declare that the following is a full, clear, and exact description thereof, reference being had to the accompanying drawings, and to the letters of reference marked theron, making a part of this specification.

This invention relates to an improved motive power, which is especially designed for operating churning and other like machines; and 15 it consists in the combination, with a helically-grooved drum rotated by a weight and cord, of a train of wheels, a winding-up device, and a driving-shaft bearing a pinion and detachably connected to the winding-up shaft of 20 the wheel-train by a pin entering an annular groove in said winding-up shaft, all of which will be fully understood from the following description, when taken in connection with the annexed drawings, in which—

25 Figure 1 is a front view of my improved churn-power. Fig. 2 is an elevation of one side thereof. Fig. 3 is an enlarged diametrical section through the winding-drum, its spur-wheels, and bearings. Fig. 4 is a diametrical 30 section through the winding-up shaft, its spur-wheels, and bearings, and the driving-shaft and its spur-wheel, showing the coupling for the driving-shaft. Fig. 5 is an enlarged sectional detail showing part of the driving-shaft 35 and winding-up shaft and their coupling.

Referring to the annexed drawings by letter, A designates a suitable standard adapted 40 to sustain in a convenient position my improved power, and A' designates a rectangular oblong plate, vertically slotted at a a and adjustably secured to said standard A by bolts and nuts a' a', as shown in Fig. 1 of the annexed drawings.

B designates a horizontal shaft, which is 45 journaled in bearings b b, secured to the plate A', and which has keyed on it a pinion spur-wheel, c, and a ratchet-wheel, d, between which wheels a large spur-wheel, C, is loosely applied on the said shaft B, and engaged with 50 it by means of a spring-actuated pawl, c', pivoted to the face of wheel C and engaging with the ratchet-wheel d, as clearly shown in Fig.

2. This shaft B, which I denominate the “winding-up” shaft, is adapted to receive a key on the squared end e. The opposite end of 55 shaft B has an annular groove, f, near one end, and on this end is fitted the socketed end of a driving-shaft, E, bearing fast on it a pinion, g. By means of a screw-threaded pin, f', entering groove f, the shafts B E are connected 60 together so that they can rotate independently of each other, as shown in Figs. 4 and 5. The pinion-wheel c on shaft B engages with a large spur-wheel, F, which is keyed on the elongated hub h of a helically-grooved winding-drum, G, from which depends a rope, w, carrying a suitable weight, W. This drum G is journaled by its hubs h h' in bearings i i, rigidly secured to the edges of the plate A', as clearly shown in Fig. 3. The large 7c spur-wheel C, which I have above described as applied loosely on the shaft B and engaged with it by means of a pawl and ratchet-wheel, engages with a pinion spur-wheel, j, keyed on one end of a shaft, H, which passes freely 75 through the hubs h h' of the hollow drum G, and has keyed fast on it a large spur-wheel, I, which engages with the pinion g on the driving-shaft E.

It will be seen from the above description 80 that by applying a key or crank on the end e of shaft B and turning this shaft in the direction indicated by the arrow on Fig. 2, the cord w can be wound upon the drum G without over-riding, and the weight W raised. The weight 85 W now acts to rotate the drum G, which, acting through the medium of wheels F c, shaft B, and the pawl and ratchet, rotates the large wheel C. This wheel in turn transmits rapid rotation to the driving-shaft E, through the 90 medium of pinion j, shaft H, and the large spur-wheel I. The shaft H has a comparatively slow rotation, and it may be utilized for giving motion to a grindstone or other device. By reason of the pin-and-groove coupling 95 between the driving-shaft E and the winding-up shaft B these two shafts receive one a fast rotation and the other a comparatively slow rotation. The slots a a through the plate allow the motor to be adjusted higher 100 or lower, as circumstances may require.

Having described my invention, what I claim, and desire to secure by Letters Patent, is—

1. The combination, in a weight-motor, of the bearing-plate, the shaft B, journaled in suitable bearings on the said plate and having keyed on it the pinion c and ratchet-wheel d, 5 the spur-wheel C, loosely secured upon the shaft B and engaging by a spring-actuated pawl with the ratchet-wheel d, the drum G, journaled in bearings on the plate A' and having one of its hubs extended beyond its 10 bearing, the spur-wheel F, keyed upon the said extended hub of the drum and engaging with the pinion c, the shaft H, passing freely through and having its bearings in the hubs of the said drum, the pinion j, keyed upon the 15 shaft H and engaging with the spur-wheel C, and the weight and its cord, substantially as described.

2. In a weight-motor, the combination of the bearing-plate, the shaft B, journaled in 20 bearings on the said plate and having keyed on it the pinion c and ratchet-wheel d, the spur-wheel C, secured loosely on the shaft B and engaging by means of a spring-actuated

pawl with the ratchet-wheel d, the drum G, journaled in bearings on the bearing-plate 25 and having keyed on one of its extended hubs or journals the spur-wheel F, which engages with the pinion c, the shaft H, passing freely through the drum G and having its bearings in the journals thereof, the pinion j, keyed 30 upon the shaft H and engaging with the spur-wheel C, the spur-wheel I, keyed upon the shaft H, the pinion g, having its bearing on and being loosely coupled to one end of the shaft B, the said pinion being located upon a 35 shaft, E, and engaging with the spur-wheel I, and the weight and its cord, substantially as described.

In testimony whereof I have affixed my signature, in presence of two witnesses, this 24th 40 day of February, 1887.

JEROME B. SWEETLAND.

CHAS. E. STRATTON,
NELSON C. BELL.

Correction in Letters Patent No. 370,026.

It is hereby certified that Letters Patent No. 370,026, granted September 13, 1887, upon the application of Jerome B. Sweetland, of Pontiac, Michigan, for an improvement in "Weight-Powers," was erroneously issued to the said "Sweetland" as owner of the patent; that said Letters Patent should have been issued to *Lincoln H. Smith* of *Council Bluffs, Iowa*, as sole owner, he being the assignee of the entire interest; and that the said Letters Patent should be read with this correction therein that the same may conform to the record of the case in the Patent Office.

Signed, countersigned, and sealed this 14th day of February, A. D. 1888.

[SEAL.]

D. L. HAWKINS,
Acting Secretary of the Interior

Countersigned:

BENTON J. HALL,
Commissioner of Patents.
